UNITED STATES PATENT OFFICE

162,488

CLOCK

Irene Winston Spier, New York, N. Y., assignor to
Beacon Plastic & Metal Products, Inc., New
York, N. Y., a corporation of New York

Application April 8, 1950, Serial No. 9,074

Term of patent 14 years

(Cl. D42—7)

To all whom it may concern:

Be it known that I, Irene Winston Spier, a citizen of the United States, residing at 25 Fifth Avenue, New York city, in the county of New York and State of New York, have invented a new, original, and ornamental Design for a Clock, of which the following is a specification, reference being had to the accompanying drawing, forming part thereof.

In the drawing

Fig. 1 is a front elevational view of a clock, showing my new design;

Fig. 2 is a side elevational view thereof; and

Fig. 3 is a rear elevational view.

I claim:

The ornamental design for a clock, substantially as shown, and described.

IRENE WINSTON SPIER.
